DESIGN FOR A BEANBAG TOY OR SIMILAR ARTICLE

Ethel D. Stafford, Webster Groves, Mo.

Application July 4, 1945, Serial No. 120,509

Term of patent 7 years

(CL. D34—15)

To all whom it may concern:

Be it known that I, Ethel D. Stafford, a citizen of the United States of America, residing at the city of Webster Groves, county of St. Louis, State of Missouri, have invented a new, original, and ornamental Design for a Beanbag Toy or Similar Article, of which the following is a specification, reference being had to the accompanying drawing, forming a part thereof.

I claim:

The ornamental design for a beanbag toy or similar article, as shown.

ETHEL D. STAFFORD.
